UNITED STATES PATENT OFFICE.

HUGO KARL SAKOWSKI, OF HELSINGFORS, FINLAND.

CONTAINER FOR MATCHES IN THE SHAPE OF BOOKS OR CARDS.

Application filed June 22, 1925, Serial No. 38,824, and in Germany May 20, 1925.

My invention relates to an improved container for matches in the shape of a book or cards. According to my invention the container consists of a continuous length of card-board or thick paper composed of or comprising eight interconnected sections or parts folded up to form a receptacle for matches which are made of or cut from a card or cards having a joint foot-piece.

- 10 One of the objects of my invention is to provide a container of the stated kind which will afford the largest possible surfaces for advertising, memorandum and other useful purposes and at the same time prevent the matches from accidental ignition. To this end I provide a safety section or flap and a reinforcing flap on the inner side of the outer cover in order to protect the ignition heads of the matches from undue pressure 20 and to obtain a large surface for use exclusively for advertisement and note purposes, the construction of the container, in other regards, being such that the heads of the matches contained therein are always 25 separated and protected from a match to be lighted or a lighted match by a double safety wall or partition.

Another object is to provide a closing means preferably in the form of a suitable 30 cut in one of the sections, shaped to form a nose or lug projecting from the face of the said section, a second nose being provided in one fold of the foot-piece of the matches to form a springy means engaging in the said cut in order to maintain the first 35 stated nose or lug in elevated position so that the transverse edge of the sections forming the cover can be readily inserted below the nose or lug.

40 With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are 50 expressed.

In the drawings forming a part of this specification two embodiments of the invention are shown by way of exemplification.

55 Figure 1 is a plan view of the continuous length of card-board or thick paper com-

prising eight inter-connected sections or parts limited by transverse folding lines;

Figure 2 is a perspective view of the container with the double card of matches therein and with the cover formed by two adjacent end sections, opened; 60

Figure 3 is a similar view with the safety flap formed by the other two adjacent end sections, opened; 65

Figure 4 is a side view of the filled container closed and shown on a larger scale;

Figure 5 illustrates a double card of matches with the joint foot-piece;

Figure 6 is a sectional view of the card 70 in folded position ready for insertion into the container;

Figure 7 is a perspective view of the other embodiment with the cover and the safety flap opened, and 75

Figure 8 illustrates a section thereof on a larger scale and with the cover and the safety flap closed.

Parts which are repeated in the several figures bear the same reference characters 80 in each case.

Referring to the drawings the match container is made from a single length of card-board or thick paper comprising eight successive or interconnected sections 1 to 8 as 85 shown in Figure 1. The section 1 is a reinforcing flap folded on the line 2' over upon the inner or back face of the section 2 which represents the outer cover of the container. Preferably the section 1 is af- 90 fixed partially, that is to say, near the fold 2', to the section 2 by means of a suitable agglutinant or in any other appropriate manner, so that the thus formed cover is a comparatively strong structure adapted to 95 resist wear and tear during the whole of its useful life and to render the advertisements thereon more effective. Further advantages of the structure are as follows: The reinforcing section 1 supports the striking surface 20, if provided on the outer face 100 of the section 2, and the double edges on the right and on the left side of the cover are particularly useful in properly handling the latter for opening and closing purposes; the fulminating heads of the matches are 105 better protected from pressure effects; the rough back face of the section 2 forming the cover properly speaking is duly masked; comparatively large surfaces for advertisements are afforded with the outer faces of the sections 1 and 2 directed towards the on-

110

looker, whereby economy in cost is ensured owing to the fact that only one side (the outer) of the strip of material shown in Figure 1 is required to be printed on, so that such printing can be effected at a single operation; the outer surface of the folded-in section 1 (see Figures 2 and 3) and any advertisements or notes thereon being readable when the cover is opened.

- 10 In order to provide the required or desirable flexibility of the cover for opening and closing purposes the reinforcing section 1 is given a somewhat shorter length than that of the section 2. The main or outer 15 cover consisting of the two sections 1 and 2 extends, when in closed position, as far as and over the connecting section 6 so that, upon closing the cover, its edge 2' will be in proximity to the edge or fold between the 20 sections 5 and 6 and thus will overlie the major portion or area of the section 6, as will be readily understood on inspection of Figure 4. This is of particular advantage 25 in case a striking surface is to be provided on the section 6 inasmuch as said surface then will be safely covered and protected by the cover 1, 2 if closed. Moreover, the cover affords on its outer face—of section 2—a large area for advertising purposes. 30 The two free corners of the cover 1, 2 are cut off as at 2" and 2'", in order to prevent the cover, on being opened or closed, from touching the fingers of the hand that holds the container, so that the fingers will not interfere with the cover at the closing operation. The cut corners also afford a more pleasant aspect.

40 The section 3 intermediate between the main cover 1, 2 and the back 4 of the container acts like a hinge, as will be clearly seen on inspection of Figures 2 to 4, and its outer face adds a further area for advertisements and the like. The back 4 is connected with the bottom section 5 which is 45 the smallest part of the length, and the rear face of the section or back 4 may also be utilized for advertisements, it being an essential feature that all of the advertisements and the like can be printed in a single 50 operation, since only one side of the length of material shown in Figure 1 is intended for advertisements, as herein before mentioned.

55 The bottom section 5 is bent upwards, see Figure 2, and the following section 6 is bent parallel with the back 4. The folded joint foot-piece of the match-card is inserted between the two sections 4 and 6 and secured in position by means of a clamp 11 60 or the like, a locking means 10 being provided on the outer face of the section 6 for holding the cover in closed position, as will be seen in Figure 4.

65 The safety section 7 projects from the section 6 along or on a fold or crease 31 acting

in the manner of a hinge to allow the section 7 to be turned up and down, as will be understood from Figures 2 to 4. The section 7 overlies the matches when a match is lighted so that accidental ignition of the 70 former is prevented for which reason it may be regarded as an inner or supplemental cover, and at the same time it offers a large supplemental area for advertising or not-ing purposes and for a striking surface 22. 75

The next section 8 is folded inwards along a crease 7', and preferably affixed to the inner face of the section 7 by means of an agglutinant or in any other suitable way. In this manner the section 7 is greatly reinforced and provides at the same time a further large surface for advertising purposes or the like, as will be seen in Figure 3.

80 The locking means 10 is preferably made of a piece of wire bent to form a gripping 85 tongue or hook for the free edge 2' of the main cover to engage in, as will be seen in Figure 4. In the embodiment shown the locking tongue 10 is located near one end of the match securing section 6 while the 90 securing clamp or wire 11 is located near the other end of the section 6 so that the intermediate portion 21 of the upper face of the section 6 may likewise be utilized for an advertisement or the like. 95

The wire or clamp 11 passes through the two sections 4 and 6 and through the folded foot portion of the match card 30 so as to firmly connect the same. The lighting or striking surface 20 may be provided either 100 on the outer face of the main cover in close proximity to the outer edge 2' thereof, as shown by dotted lines in Figure 2, or on the outer face of the supplemental cover or safety flap 7, as at 22, in close vicinity of 105 the joint crease 31. In either case the surface 20 or 22 can not, owing to the particular location thereof, serve its purpose or, in other words, a match can not be lighted, unless the heads of the matches within the container are covered and protected by at least one double layer of card-board or the like, that is to say, the safety flap constituted by the two sections 7 and 8.

110 A specific construction of the match-card 115 is illustrated in Figure 5. The joint foot portion 30' of the card 30 has a transverse crease 30² along which the card is folded so as to adopt the shape shown in Figure 6 120 with the two rows of matches 30³ and 30⁴ in juxtaposition. The single matches of the row 30³ or 30⁴, however, are not in alignment or in one and the same plane, but they diverge therefrom alternately and the heads 125 are in staggered relationship, as will be readily seen in Figures 6 and 7.

130 In one fold or part of the joint foot portion 30' a cut or slot 30⁵ is provided and this slot is shaped to form a nose 30⁶ adapted to be turned outwards, when the card

is folded as shown in Figure 6, owing to the springy action of the material. In assembling the parts to form a container with the match-card inserted, as shown in Figures 7 and 8, the said nose 30° will lie below the locking nose or tab 40 and thus will act to lift the tab and hold the same in a position ready for the reception of the edge 2' of the cover constituted by the sections 1 and 2, as will be clearly understood from an inspection of Figures 7 and 8. In this case the wire or clamp 41, connecting the container with the match-card is provided at a place intermediate the crease 31 and the cut forming the nose or tab 40. It will be evident that my invention, whilst still adhered to in its main essentials, may be varied in many ways, according to the several requirements desired or most suitable under different circumstances.

What I claim is:

1. A container for matches in the shape of a book or cards, made of a single, continuous strip of material consisting of eight interconnected sections, to wit: a cover, a reinforcing section for the cover folded against the inner face thereof, a back section, a top section connecting the adjacent edges of the cover and the back section, a match-securing section at the front of the container, a bottom section between the match-securing and back sections and connecting the lower edges thereof, a safety section connected to the upper edge of the match-securing section, and a reinforcing section folded against the inner face of the

safety section; the arrangement being such that the several sections are folded in one and the same direction.

2. A match container, according to claim 1, in which one reinforcing section is permanently secured to the inner face of the cover, and the other reinforcing section is permanently secured to the inner face of the safety section. 40

3. A container for matches in the shape of a book or cards, made of a single, continuous strip of suitable material adapted to be printed on its entire front face in a single operation, and folded in one and the same 50 direction to form a plurality of interconnected sections including a cover, and a reinforcement for the cover of substantially the same size as the latter; said reinforcement being folded backward and having its rear face secured flat against the rear face of the cover, whereby the printed front face of the strip appears visible when the container is opened. 55

4. A container for matches in the shape of a book or cards, made of a continuous length of suitable material comprising a plurality of interconnected sections including a cover and a match securing section, 60 a locking lug on said match securing section, and a springy nose on the foot portion of the match book to press said lug outwardly 65 into position for the reception of the closing edge of the said cover.

In testimony whereof I have affixed my 70 signature.

HUGO KARL SAKOWSKI.
